CLIFF R. CRAWFORD, OF MIDDLETOWN, OHIO, ASSIGNOR TO THE BLACK-CLAWSON COMPANY, OF HAMILTON, OHIO, A CORPORATION OF OHIO

PAPER MACHINERY

Application filed August 20, 1930. Serial No. 476,563.

This invention relates to apparatus for forming a web of fibrous material such as fiber board or the like.

One object of the invention is the provision of a fiber board forming apparatus having a single forming screen on which stock fibers are collected as it moves through a vat, and a pressure roll above the stock level of the vat for compressing the collected pulp 10 on the forming screen, the pressure roll being rotated at the same surface speed as the forming screen.

Another object of the invention is the provision of an apparatus of the character mentioned, having a cylindrical forming screen, and a screen surfaced pressure roll for compressing the stock fibers collected on the forming screen and for withdrawing water thereinto while compressing the fibers into 20 a moist thick web.

A further object is the provision of a fibrous board forming apparatus having a foraminated pressure roll for withdrawing water while compressing the fibers collected on 25 the forming screen, together with a smoothing roll cooperating with the surface of the forming screen.

Still another object is the provision of a paper board forming apparatus in which 30 the moist web travels tangentially from the forming screen in a straight line to the nip of pressure rolls, after being compressed on the surface of the forming screen.

Other objects and advantages of the invention will be apparent from the following 35 description, the appended claims and the accompanying drawings in which—

Fig. 1 is a side elevation, shown partly in section, of a web forming apparatus embodying the present invention;

Fig. 2 is a section on the line 2—2 of Fig. 1, parts being broken away and shown in section; and

Fig. 3 is a detail view, in section, of the 45 forming screen.

Referring more particularly to the drawings, in which a preferred embodiment of the invention is illustrated, 10 designates generally a tank or vat of a fibrous board forming machine. Rotatable within the vat is a

forming cylinder designated generally 11. Suitable bearings may be provided at or near opposite sides of the vat for rotatably supporting the shaft 12 of the forming cylinder, which is rotated at a suitable speed from a 55 drive wheel 13 or any other suitable source of power.

The vat is supplied in any suitable manner with fibrous stock or pulp in a rather thin fluid state, so that the level of the pulp as indicated at 17 is somewhat below the top of the vat, and preferably well below the top 60 of the forming cylinder.

The forming cylinder, which may have a diameter of 10 or 15 feet or more, has a foraminated surface, preferably in the form of a wire screen 18 of about fourteen inch mesh. This screen is supported on heavier circumferentially extending wires 19 as shown in Fig. 3, which in turn are supported upon 70 transverse bars 20 to provide a rigid structure, the bars 20 being supported at spaced intervals by annular rings or walls 21 which project outwardly from the rigid cylindrical metal cylinder 22. The cylinder 22 is supported at spaced intervals by heavy hollow spokes 23 which project radially from the hollow shaft 12. Adjacent the end of each spoke 23 there is an opening 24 in the shaft 12 and an opening 25 in the cylinder 22. A 75 number of rings or walls 26 extend radially parallel to the shaft axis between the cylinder 22 and the wire screen, dividing the periphery of the forming cylinder 11 into a large number of segmental areas each being 80 in communication through the hollow spokes with a passage 28 in the forming cylinder shaft. The number of these passages 28, which extend axially of the forming cylinder shaft, correspond to the number of seg- 85

mental areas in the periphery of the forming cylinder, and any number of the segmental areas in the periphery of the forming cylinder may be placed under suction by suitable control of a regulating disk 29 leading to a suction manifold 30 preferably at the end of the shaft 12. The pipe 31 which is in communication with the suction manifold 30, extends to a suction pump or the like. It will be understood that those segmental areas between the 90

walls 26 which are below the level of the stock in the vat may be placed under suction, while suction is not applied to those segmental areas that project above the pulp level, the controlling disk 29 providing for the control of the suction in such a way that any desired rotation of the forming cylinder may take place after a particular segmental area has moved below the surface of the stock, before suction is applied to it.

The forming cylinder rotates in a clockwise direction, see Fig. 1, part or all of the screen surface of the cylinder below the level of the pulp being under suction, and during its rotation there is a gradual accumulation of the fibers of the stock on the forming surface as the water constituent of the stock drains through the screen. The suction may start at a point 33 for example so that the water flows into the forming screen from this point up to where the forming screen leaves the stock in the vat, where the collection on the surface of the forming screen will be possibly several inches in thickness, the denser portion of the partially formed mass being of course against the surface of the forming screen. While the forming cylinder has been herein described as a suction cylinder, it should be understood that the vat can be arranged at one side only of the forming cylinder so that the water draining into the forming cylinder can merely flow down to the bottom and then through its surface screen to a collecting chamber.

Just above the level of the stock in the vat is a rotatable roll 35 which is adapted to compress the partly formed web of collected fibers on the surface of the forming screen. Preferably this roll 35 has a foraminated cylindrical surface of at least two or three feet in diameter. As shown, the roll 35 is journaled in bearings 36 which are supported by arms 37 hung pivotally at 38 from bracket supports 39, springs 40 being provided for pressing the suspended roll towards the forming screen. The springs 40 may be of such size as to create a pressure of several hundred pounds per inch roll length so that as the pulp or fiber collection moves through the nip of the rolls 11 and 35, it is compressed and some of the water extracted, leaving a moist thick sheet or web of matted fibers on the upwardly moving surface of the forming cylinder. The surface of the pressure roll 35 is preferably a wire screen 41 supported on a suitable frame 42, of any suitable character. This pressure roll, having a foraminated surface, and being at one side of the forming cylinder but above the level of the stock in the vat, effectively withdraws a quantity of the water from the partly formed web, while compressing the same against the surface of the forming screen. The interior of the roll 35 may be placed under suction if desired, but it is preferred

that the water that is withdrawn into the roll should merely flow down to the bottom of the roll by gravity and then out through its screen surface, being returned to the vat or removed by a suitable baffle 44. It will thus be apparent that water is withdrawn from both sides of the partially formed fiber sheet on the forming cylinder, as it passes through the nip of the rolls 35 and 11. As previously mentioned, the diameter of the pressure roll 35 is two or three feet or more, and this roll is positively driven at the same surface or peripheral speed as the forming cylinder 11, being connected by suitable transmission devices 46, to the driving wheel 13, so that the partly formed stock gathered and matted on the surface of the forming cylinder will not be disturbed while being compressed by the roll 35.

After passing by the pressure roll 35, the moist thick fiber sheet or web on the forming cylinder is moved along to a smoothing cylinder 47. The surface of this cylinder is preferably of rubber, although it may be made of fine wire mesh, if desired. Axle shafts 48 at the ends of the smoothing roll 47 are carried in suitable bearings 49 which are supported by springs 50 and 51. The springs 51 are adapted to support the weight of the roll 47 and its bearings when fully compressed, so as to maintain a minimum distance of an inch or two depending upon the desired thickness of the fiber board, between the peripheries of the smoothing roll 47 and the forming cylinder 11. The springs 50 exert a controlled pressure downwardly upon the roll 47, this pressure being governed by hand-wheels 53 so that a pressure of several hundred pounds per inch roll length may be applied to the moist fiber sheet on the forming cylinder. If a mass of pulp of extra large thickness should come up to the smoothing roll 47 it can move upwardly in a yielding manner due to its spring support, permitting the large mass of pulp to pass through. The roll 47 smooths out the surface of the web, which may be ridged or grooved by the foraminated surface of the roll 35, and also serves to further compress and force water from the web so it may leave the nip of the roll 47 in a semi-rigid state and dry enough to be practically self-sustaining.

The smoothing pressure roll 47 is located preferably centrally above the forming cylinder so that the moist board web leaves the forming cylinder tangentially in a substantially horizontal direction, and travels in a straight line to a series of press rolls 55. These press rolls are provided in pairs, as shown, so that the board web 56 passes through the press rolls in a straight line, thus avoiding any bends in the web from the time it leaves the nip of the roll 47 until it is compressed and further dried by the press rolls 55, which leave the sheet in a practically

rigid stiff condition. Heretofore the partly formed sheet when leaving the forming cylinder has not been moved in a straight line tangentially from the forming cylinder and consequently the bends that obtain in the sheet loosened the formation and weakened the sheet as the matted condition of the fibers was disturbed. In accordance with the present invention however, this objectionable defect of the prior practice is entirely obviated and the final product is very strong and of a dense and homogeneous character.

It will be apparent that all of the fibers of the finished board will be closely interwoven and intimately held together as the board web leaves the forming cylinder, as there is only a single forming screen subjected to the stock, and there will be no tendency for the board to split centrally as might be the case if two forming screens were used in conjunction to press two separate portions of collected fiber mats together. The withdrawal of water from both sides of the partly formed web, that obtains at the nip of the screen surfaced pressure roll 35 and the forming cylinder 11 is so effective that a smoothing roll such as the roll 47 need not be employed, this roll 47 being particularly useful however to smooth the surface of the sheet and to further compress the sheet and further dry the same. The smoothing roll 47 is preferably driven by a suitable transmission or drive 58 so that it moves at the same surface speed as the forming cylinder, and thus it will not disturb the surface of the formation of the wet sheet that it engages.

While the form of apparatus herein described constitutes a preferred embodiment of the invention, it is to be understood that the invention is not limited to this precise form of apparatus, and that changes may be made therein without departing from the scope of the invention which is defined in the appended claims.

45 What is claimed is:

1. Apparatus for manufacturing fibrous board comprising a stock vat, a single forming screen for said vat on which stock fibers are collected and comprising a forming cylinder, a rotatable pressure roll having a foraminated surface cooperating with the upwardly moving portion of said forming screen at one side of the forming screen near the stock level of the vat, said pressure roll being adapted to withdraw water thereinto while compressing the collected fibers against the forming screen, a smoothing roll cooperating with the top of the forming screen, and pressure rolls for compressing the board web after it leaves the forming screen and so arranged that the board web comes to the nip of said pressure rolls in a substantially straight line substantially tangentially from the forming screen and the smoothing roll.

2. Web forming apparatus of the class described comprising a stock vat, a rotatable forming cylinder having a foraminated surface in said vat on which stock fibers are collected, a rotatable pressure roll having a foraminated surface cooperating with the surface of the forming cylinder for compressing the pulp collected thereon, said pressure roll being provided above the stock level of the vat and at one side of the forming screen for withdrawing water thereinto while compressing the fibers against the forming cylinder, means for positively driving said pressure roll and said forming cylinder at the same peripheral speed, and pressure rolls for compressing the fibrous web after it leaves the forming cylinder and so arranged that the fibrous web comes to the nip of said pressure rolls in a straight line substantially tangentially from the forming cylinder.

3. Web forming apparatus of the class described comprising a stock vat, a forming cylinder for said vat having a foraminated surface on which stock fibers are collected, a rotatable pressure roll above the pulp level of the vat having a foraminated surface cooperating with the surface of the forming cylinder for compressing the fibers collected thereon, said pressure roll cooperating with an upwardly moving side of said forming cylinder, a second pressure roll above said forming cylinder having a smoothing surface cooperating with the forming cylinder, and means for driving said forming cylinder, said rotatable pressure roll and said second pressure roll at the same peripheral speed.

4. Apparatus for manufacturing fibrous board comprising a stock vat, a forming screen for said vat on which stock fibers are collected, a pressure roll cooperating with the surface of the forming screen, and pressure rolls for compressing the board web after it leaves the forming screen and so arranged that the board web comes to the nip of said pressure rolls in a straight line tangentially from the forming screen and tangentially from the first said pressure roll.

5. Apparatus for manufacturing fibrous board comprising a stock vat, a cylindrical forming screen for said vat on which stock fibers are collected, a pressure roll cooperating with the surface of the forming screen, and pressure rolls arranged in pairs for compressing the board web after it leaves the forming screen and so arranged that the board web comes to the nip of said pressure rolls in a straight line tangentially from the forming screen and tangentially from the first said pressure roll.

In testimony whereof I hereto affix my signature.

CLIFF R. CRAWFORD.
